UNITED STATES PATENT OFFICE

CHARLES B. KENNEDYE, OF UNIVERSITY CITY, MISSOURI, ASSIGNOR TO THE KENNEDYE CORPORATION, OF WILMINGTON, DELAWARE, A CORPORATION OF DELAWARE

WELL-DRILLING TOOL OF THE ROTARY TYPE

Application filed February 2, 1925. Serial No. 6,306.

Many difficulties have been experienced in drilling wells of relatively great depth. For instance, in drilling through formations of varying degrees of hardness, the bits become 5 dull and do not drill a hole of uniform diameter. Or, a hard spot in the formation may force the drill out of vertical line, producing a "kink" in the side walls of the hole. Or, a projecting stone loosened by the drill 10 may protrude inwardly beyond the periphery of the hole, causing the casing, when lowered into place, to stick and bind. Very frequently, proper placement of the casing is prevented because the walls of the drilled 15 hole are neither smooth nor exactly vertical. These difficulties and conditions require that the casing be raised and withdrawn to permit reaming of the hole to proper size to allow the casing to be lowered into place. Also, 20 the bits must be withdrawn to permit resharpening.

To obviate these time-consuming and expensive steps, I have devised, and my invention has for a primary object, the provision 25 of a well-drilling tool comprising drilling and reaming bits of novel construction for the economical and efficient accomplishment of the dual operations of drilling and reaming at the same time.

My invention has for another object the provision of a tool of the type stated comprising a body or stock and a plurality of detachable bits that may be readily and conveniently removed and replaced. The stock 35 and bits are so constructed that the bits, when in operative position, are firmly and securely held against accidental displacement.

My invention has for a still further object the provision of a tool of such construction 40 that water under pressure is discharged directly upon the cutting edges of the bits and upon the bottom of the hole being drilled, with the result that the drilling of the well is greatly facilitated.

My invention has for a still further object 45 the improvement of rotary well-drilling tools.

In the accompanying drawing, Fig. 1 is a view, partly in elevation and partly in longitudinal section, of a rotary well-drilling tool 50 embodying my invention.

Fig. 2 is an enlarged transverse sectional view of the tool taken approximately on the line 2—2 of Fig. 1.

Fig. 3 is an enlarged fragmental longitudinal sectional view of the tool, and

Figs. 4 and 5 are detail sectional views of the tool taken, respectively, on the lines 4—4 and 5—5 of Fig. 3.

Referring more in detail to the drawing, A designates the body or stock of the tool, which is constructed of suitable metal and is of suitable weight and dimensions. Body A, at a point 1 intermediate its ends, has its greatest diameter. From portion 1 to its lower end it is longitudinally cut-away 60 upon opposite sides to form opposed faces 2, sinuous in surface contour transversely of the stock in simulation of the tail of a fish.

From intermediate point 1, the body A is extended upwardly and may be provided with an integral extension 3 terminating in a threaded socket 4 adapted to receive the threaded end of the drill-tubing (not shown). The full strength of the bit-stock 70 A is thereby retained, and thus, the use of a separate drill-collar, with its inherent weaknesses is obviated; sharp corners in the body and jumping of pins are eliminated, and tendency toward fractures in the body 75 A is reduced to a minimum. Such construction also obviates breaking of the bit-stock at the point of connection with the separate drill-collar, thus greatly increasing the strength, durability, and efficiency of the 80 tool.

Opening to opposite sides of the stock A and extending downwardly from the intermediate portion 1 are slots 7. Each slot is provided at its base with communicating 85 grooves 8. Suitably formed in stock A at the base and adjacent the upper end of each slot 7, is a recess 9 forming a shoulder 10.

Also formed in and disposed at the lower end of the stock A, is a pair of cross-slots 11. The slots 11 open to the lower end and to sides of the stock A and are in communication with the respective slots 7. The slots 11 may be disposed obliquely to the longitudinal axis of stock A and may extend inwardly from opposite sides to somewhat 100

beyond the longitudinal axis of stock A where they overlap.

Removably fitting in and adapted for side-wise slidable accommodation in the slots 11 are individual drilling bits B having preferably the outer and cross-sectional contour best seen in Figs. 1, 3 and 5. Each bit B may comprise a wedge-shaped body 12 of greater length longitudinally of the tool at its outer side than at its inner side, and a dished or concavo-convex lower cutting end 13 whose cutting edge 14 is gradually rounded or arcuated from the outer lower corner 15 to its inner lower corner 16. In use, the concave surfaces of the cutting ends 14 are disposed on the side of the direction of rotation; their longitudinal axes are parallel, but off-set, corresponding to the obliquely disposed, overlapping arrangement of the slots 11, the contour of the lower cutting ends 13 and their cutting edges 14 completing the resemblance of the stock A and bits B to a fish-tail.

Similarly removably fitting in and adapted for endwise slidable accommodation in the slots or ways 7, are individual reaming-bits C, having preferably the outer and cross-sectional contour best seen in Figs. 2 and 4. Each bit C comprises a suitably elongated substantially rectangular body 17 gently rounded upon its outer face 18, and provided longitudinally at its inner side with tongues 19 for reamer retaining engagement with the grooves 8 at the base of the slots 7. Upon their inner faces and adjacent their upper ends, the bits C are provided with spring members 20 adapted for disposition within the recesses 9 and for engagement with the recess-shoulders 10 for removably or detachably locking the bits C from endwise upward displacement in the slots 7. In passing, I may say that, by means of a suitable tool (not shown) projected through a suitable channel or way 21 in stock A, the springs 20 may be depressed and disengaged from shoulders 10 to permit endwise removal of the bits C. Each bit C may be cut away at its lower end, as at 22, for interengaging with the cooperatively cut-away outer corner 23 of the adjacent drilling-bit B for releasably locking the bit B from sidewise removal from its slot 11.

Formed in approximately the longitudinal center of the body A is a water duct or channel 24, which duct extends from the upper end of stock A, where it is in open communication with an inlet channel 25 in the tubing 5, to a point 26 adjacent the slots 11, where channel 24 divides into oppositely disposed branch ducts 27, opening on the outer surface 60 of stock A and terminating in longitudinal surface grooves 28, for conducting the discharging water directly upon the drilling bits B, thus flushing said bits and keeping them clean. It will be understood that water under considerable head is forced along the cut-

ting surfaces of the drilling bits B, and upon the bottom of the hole being drilled, in such a manner as to remove loose matter from the well, and also to keep the bits B substantially free from accumulated dirt, stone-dust and the like.

In use and operation, the drilling-bits B are first placed in the slots 11. The reaming bits C are then slidably disposed in slots 7, the bits C interengaging at their lower ends 22 with the upper outer corners 23 of bits B, the springs 20 interlocking with the shoulders 10. The reamers C are thus efficiently locked against endwise displacement and the bits B, in turn, are securely held by the reamers C from sidewise displacement, the wedge-like engagement between bits B and stock A, securely retaining bits B from edgewise separation from the stock. It will be evident, however, that, by disengagement of springs 20 from the recess-shoulders 10, reamers C may be slidably removed from slots 7; the bits B, in turn, may be conveniently removed from slots 11, both reamers C and bits B being then readily repaired or replaced as conditions may require.

It will be observed that the engagement of the drilling-bits B provides a sufficient bearing surface to enable bits B to withstand the weight imposed by stock A and drill-tub- 95 ing 5.

In practice the bits B extend outwardly beyond stock A and slightly beyond the arcuated faces 18 of the reaming-bits C, forming straight lines parallel with the longitudinal axis of the stock A. Thus, the diameter of the hole being drilled is uniformly maintained. The outer faces 18 of reamers C present no cutting edge and efficiently function in the rotary actuations of stock A in smoothing and straightening the walls of the hole being drilled.

Thus, by means of my new tool, both reaming and drilling operations may be accomplished and effected at the same time. Both reaming and drilling bits may be inexpensively repaired or replaced. I may add that my new tool has been found exceedingly efficient in use and operation; it is relatively inexpensive in maintenance; it facilitates, and largely reduces the cost of, well drilling, and it accomplishes fully the objects and purposes hereinbefore stated.

Having thus described my invention, what I claim and desire to secure by Letters Patent is:

A well-drilling tool, including, in combination, a head having a point of greatest cross section intermediate its ends and longitudinally decreasing in cross section from that point to its lower end, and sinuous in surface contour in simulation of the tail of a fish, slots transversely disposed at the lower end of said head, drilling elements removably mounted in said slots, elongated slots in the

side of said head, reamers adapted to be removably mounted in the elongated slots having surfaces projecting beyond the sides of said head, said reamers interlocking with the drilling elements to hold same in place.

5 In testimony whereof, I have signed my name to this specification.

CHARLES B. KENNEDYE.
